DRY SHAVER

John S. Weaver, Allentown, Pa., assignor to Artie R. Harris, Kansas City, Mo.

Application July 26, 1938, Serial No. 221,415

12 Claims. (Cl. 30—43)

This invention relates to an improved dry shaving razor adapted to be operated by engagement with and movement relatively to the surface to be shaved.

It is an aim of this invention to provide an improved razor of the dry shaving type which will be manually actuated by engagement with the skin to be shaved to produce a shearing action to cut the hair from the skin.

More particularly, it is an object of this invention to provide a stationary cylinder and a rotary cylinder mounted on said stationary cylinder, said cylinders being provided with slotted openings disposed at an angle to receive the hairs to be shaved, said inner cylinder being provided with sharpened edges along the opposite sides of its slots to produce a shearing action as the outer cylinder is revolved relatively to the inner cylinder.

Still a further object of the invention, is to provide a handle portion for said cylinders having a yoke shaped head adapted to be removably attached to the opposite ends of said stationary cylinder for removably mounting said cylinder on the handle.

Other objects and advantages of the invention will hereinafter become more fully apparent from the following description of the drawing, which illustrates a preferred embodiment thereof, and wherein:

Figure 1 is a side elevational view partly in section of the razor.

Figure 2 is a fragmentary end view in elevation of the same.

Figure 3 is an enlarged cross sectional view taken on the line 3—3 of Figure 1.

Figure 4 is a side elevational view partly in section of the inner cylinder.

Figure 5 is an end view in elevation of the same.

Figure 6 is a view similar to Figure 4 of the outer, rotary cylinder.

Figure 7 is an enlarged fragmentary view partly in section and partly in elevation of the intermediate portion of the outer cylinder.

Figure 8 is a view similar to Figure 7 of the inner cylinder, and

Figure 9 is a fragmentary side elevational view partly in section showing the yoke shaped head and a portion of the handle.

Referring more particularly to the drawing, wherein like reference characters designate like or corresponding parts throughout the different views, 10 designates the handle of the dry shaving razor which is provided with the yoke shaped

head 11 formed integral therewith and disposed transversely of one end thereof, said head being formed of a resilient material, and having outwardly extending ends 12 provided with the elongated openings 13.

An inner cylinder designated generally as 14 is provided with the reduced ends 15, formed by reducing said cylinder along its top and sides, the ends 15 being shaped and sized to fit the openings 13 and being removably mounted therein to rigidly support the cylinder 14. As best seen in Figure 4, the cylinder 14 is provided with a plurality of diagonally disposed parallel slots 16 arranged along its opposite sides forming therebetween the portions 17 which, as best seen in Figure 3, are sharpened along their outer edges as indicated at 18 to provide cutting edges along the opposite sides of the slots 16.

A cylinder, designated generally as 19, is adapted to be rotatably mounted on the intermediate cylindrical portion of the cylinder 14, said cylinder being provided with a relatively thin intermediate portion 20 and with the thickened tapering ends 21. The intermediate portion 20 is provided with the transversely disposed oblong openings 22, arranged in rows around said cylinder, said openings being disposed in staggered relationship, as best seen in Figure 6. Portion 20 is provided with the outwardly projecting pointed members 23 disposed between the opposite ends of each of the adjacent openings 22, so that each opening 22 is provided with a prong or projection 23 at each end and at each side thereof, said projections forming a serrated face adapted to cooperate with the serrated outer face of the ends 21, for a purpose which will hereinafter be described.

The opposite ends of the cylinder 19 are chamfered at 24 to engage the inwardly projecting annular beads 25 on the ends 12. The beads 25 are beveled on their outer sides to fit the chamfered faces 24 thereby forming bearings to cooperate with the stationary cylinder 14 for rotatably mounting the outer cylinder 19.

As heretofore mentioned, the yoke shaped head 11 is formed of a resilient material so that the ends 12 may be sprung outwardly relatively to each other for inserting or removing the two cylinders, which are assembled before being inserted in the head 11 and which may be disconnected from each other after being removed from the head.

The razor is operated as follows: with the handle 10 held relatively close to the skin of the face, the roller 19 is pressed against the skin

and the serrated face thereof will cause a frictional engagement so that when the razor is moved backwards or forwards over the skin the outer cylinder 19 will revolve relatively to the inner cylinder 14, on which it is mounted. The hairs on the skin will project through the oblong openings 22 and into the slots 16 to be sheared off by the cutting edges 18 as the openings 22 move out of communication with the slots 16. Openings 22, are sufficiently long so that the hairs, to be cut, will not be withdrawn therefrom before coming in contact with one of the cutting edges 18. Slots 16 are disposed on opposite sides of the razor, as best seen in Figure 3, so that the razor may be turned over and either side thereof used, and both of the longitudinal sides of each of the slots 16 are sharpened so that the razor may be pulled or pushed or actuated by a reciprocating motion. The hairs which are cut by the shaver will be deposited within the cylinder 14 and may be blown out of either of the open ends 26 thereof without disconnecting the cylinders 14 and 19. The diverging or beveled ends 21 of the cylinder 19 are shaped to properly fit the contours of the human face and the angles of said portions may be varied to correspond to different general contours of the face, which may exist. Since the cylinder 19 is pressed tightly against the face, the side which is in engagement with the face will be forced inwardly against the adjacent portion of the cylinder 14 thereby forming a tight fit to insure a proper shearing cut between the edges 18 and the ends of the oblong openings 22.

Various modifications and changes may obviously be made and are contemplated, as the drawing and description are only intended to illustrate a preferred embodiment of the invention, and the right is therefore reserved to make such variations and changes as fall within the spirit and scope of the invention as hereinafter defined by the appended claims.

I claim as my invention:

1. In a device of the class described, a handle member having a yoke formed on one end thereof, the opposite outwardly extending ends of said yoke being provided with elongated openings, a cylinder having reduced elongated ends sized to fit said openings to rigidly mount the cylinder in said yoke, said cylinder being provided with oppositely disposed rows of diagonal slots, said cylinder being sharpened on the opposite sides of said slots to form cutting edges, a cylinder rotatably mounted on said first mentioned cylinder and provided with a plurality of transversely disposed oblong openings arranged at an angle to said slots and the openings in said outer cylinder, when revolved, cooperating with the slots to produce a shearing action, and the opposite ends of said rotary cylinder being enlarged and diverging to adapt said cylinder to the contours of the face.

2. In a device of the class described, a handle member having a yoke formed on one end thereof, the opposite outwardly extending ends of said yoke being provided with elongated openings, a cylinder having reduced elongated ends sized to fit said openings to rigidly mount the cylinder in said yoke, said cylinder being provided with oppositely disposed rows of diagonal slots, said cylinder being sharpened on the opposite sides of said slots to form cutting edges, a cylinder rotatably mounted on said first mentioned cylinder and provided with a plurality of transversely disposed oblong openings arranged at an angle

to said slots and the openings in said outer cylinder, when revolved, cooperating with the slots to produce a shearing action, and said outer cylinder being serrated to prevent it from slipping relatively to the surface with which it is in engagement.

3. A razor comprising a stationary cylinder provided with diagonally disposed slots, said cylinder being sharpened along the opposite sides of said slots, and a cylinder rotatably mounted on said stationary cylinder and provided with a plurality of transversely disposed oblong openings communicating with said slots and disposed at an angle thereto, said outer cylinder being serrated on its outer side to adapt it to be revolved by engagement with a surface, and said openings and slots being adapted to receive hair projecting outwardly from said surface to be sheared off by engagement with the cutting edges of said inner cylinder.

4. A device as in claim 3, said inner cylinder being provided with reduced elongated ends, and a handle having a yoke shaped head provided with elongated openings in its opposite ends to receive the ends of said inner cylinder to support said cylinder.

5. In a dry shaver, a handle having a yoke shaped head, a stationary cylinder removably mounted in said head, said cylinder being provided with rows of diagonally disposed slots, said cylinder being provided with cutting edges extending the length of the opposite sides of said slots, and a cylinder rotatably mounted on said stationary cylinder and provided with transversely disposed oblong openings communicating with said slots and disposed at an angle thereto, the outer surface of said last mentioned cylinder being serrated and provided with diverging ends.

6. A shaving device including a sleeve-like shearing member of extreme thinness and provided with openings, a cutter within said sleeve and having a cutting edge cooperating with edges of the openings to provide a shear cut, means mounting the sleeve for movement around said cutter, and means supporting said cutter in a fixed position relatively to said shearing member.

7. A device of the character described, including a stator having cutting means, a guard comprising an endless band having cutting edges cooperating with the cutting means of the stator and rotatable about the exterior of the stator with said cutting edges moving successively across said cutting means, and means retaining the stator in a fixed position within the guard.

8. A manually operable dry shaver including a non-rotary cylindrical cutter element having longitudinally extending peripheral cutting teeth, and an outer hollow cylindrical cutter element having perforations defining cutting teeth, said outer cutter element surrounding the non-rotary cutter element and mounted thereon to freely turn with reference thereto for cutting engagement with the teeth of the inner cutter element when pressed against and rolled over the skin so as to shear the hair protruding through the perforations and extending into the path of the teeth of the inner cutter element.

9. A manually operable dry shaver including a non-rotary cylindrical cutter element having longitudinally extending helical peripheral cutting teeth, and an outer hollow cylindrical cutter element having perforations defining cutting teeth, said outer cutter element surrounding the non-rotary cutter element and mounted thereon to freely turn with reference thereto for cut-

ting engagement with the teeth of the inner cutter element when pressed against and rolled over the skin so as to shear the hair protruding through the perforations and extending into the path of the teeth of the inner cutter element.

10. A dry shaving device comprising in combination a frame, a hollow cylinder freely rotatable in said frame, the walls of said cylinder being very thin and provided with small perforations, and a cutting element fixed to said frame and disposed within said cylinder, said cutting element having its cutting edge in contact with, or close to the internal surface of said cylinder, whereby by moving the cylinder over the face of the user said cylinder is caused to rotate relatively to said cutting element.

11. A dry shaver comprising a frame, a hollow cylindrical face engaging member mounted on said frame for free rotation about the axis of the cylinder whereby it will be rotated by traction as the frame is moved across the face, said cylindrical member having an opening therein providing a cutting edge, a second member provided with a cutting edge, means for supporting said second member with its cutting edge sta-

tionary and in adjacency to the inner surface of the cylindrical member, the cylindrical member being free to rotate relatively to said second member and its cutting edge, and said second member being held against rotation with the cylindrical member, whereby a relative movement will be effected between the aforementioned cutting edges by traction as the frame is moved across and in engagement with the face.

12. A dry shaver comprising a frame, a face engaging member mounted on said frame for free movement on the frame whereby it will be actuated by traction as the frame is moved across the face, said member having an opening therein providing a cutting edge, a second member provided with a cutting edge, and means for supporting said second member on the frame with its cutting edge stationary with respect to the frame and in contact with the inner surface of said movable member whereby a relative cutting movement will be effected between the aforementioned cutting edges by traction as the frame is moved across the face.

JOHN S. WEAVER.
